UNITED STATES PATENT OFFICE

FREDERICK J. SHEPARD, JR., OF AUBURNDALE, AND NATHANIEL WARSHAW, OF BOSTON, MASSACHUSETTS, ASSIGNEES TO LEWIS-SHEPARD COMPANY, OF WATERTOWN, MASSACHUSETTS, A CORPORATION OF MASSACHUSETTS

PORTABLE HOISTING MACHINE

Application filed October 17, 1928. Serial No. 313,018.

This invention relates to improvements in portable hoisting machines and the object thereof is to provide a simple and convenient device for raising articles to a considerable height and transporting them from one place to another.

More particularly the object of the invention is to provide a hoisting machine of this character which is adapted to be used for assembling and removing relatively heavy articles from a recess or receptacle, such for example as for removing the power unit of a refrigerating plant from the refrigerator. In certain types of refrigerators the power unit is contained in an upper compartment of the refrigerator and is introduced and removed through the top thereof. Such a power unit is of considerable weight and fits quite closely within the upper compartment of the refrigerator. It is consequently difficult to assemble in and remove the same from such compartment. The present invention is designed not only to facilitate such assembling and removing of the power mechanism in factories where the refrigerators are assembled, but also which will be of convenient size and character to be transported to houses and apartments where such refrigerators are in use and readily employed to remove the power unit for repair or replacement.

Another object of the invention is to provide a hoisting machine comprising a base frame which is formed of structural steel bars welded together to produce a light, integral, rigid construction.

A further object of the invention is to provide a portable hoisting machine of this character with a standard formed of assembled structural steel members, preferably in the form of channel bars, adapted to provide a guideway for a load-supporting means.

A further object of the invention is to provide a standard construction which can be readily attached and detached from the base of the machine for purpose of transportation.

Another object of the invention is to provide a hoisting machine of the type described with a novel form of load-supporting means

comprising a vertical sliding member mounted in the standard having at its upper end an arm overhanging the base so that the articles to be raised may be supported at a considerable distance from the standard. By virtue of this construction the base frame of the hoisting machine may be inserted beneath a refrigerator and between the legs thereof and the end of the overhanging arm positioned above the power unit, or other article to be hoisted, so that when the latter is attached thereto the load-supporting means may be elevated to raise the article out of its receptacle and the hoisting machine thereafter removed to transport the same to another convenient place, or, where the article, such as the power unit is to be introduced into a chamber, such as the open top of a refrigerator, the power unit may be supported upon the overhanging arm and carried by the portable hoisting machine into such position that it can be lowered directly into the chamber without danger of injuring the walls thereof.

Another object of the invention is to provide a novel form of load-supporting means formed of assembled, structural bars or plates welded together to provide a rigid, but light construction.

Another object of the invention is to provide a load-supporting means of this character having an overhanging arm which is so constructed that the overhanging arm can be raised above and lowered below the upper end of the standard.

Another object of the invention is to provide the overhanging arm with simple and convenient means which may be readily attached and detached to the standard and to the article to be hoisted.

Another object of the invention is to provide a preferably integral frame construction with novel means for securing the supporting wheels or casters thereto.

These and other objects and features of the invention will more fully appear from the following description and the accompanying drawings and will be particularly pointed out in the claims.

A preferred embodiment of the invention

is illustrated in the accompanying drawings, in which,

Fig. 1 is a side elevation, a portion of the standard being broken away to show the manner in which the load-supporting means is guided and supported therein;

Fig. 2 is a front elevation of the construction illustrated in Fig. 1;

Fig. 3 is a plan view of the same;

Fig. 4 is an enlarged transverse sectional view on line 4—4 Fig. 1; and,

Fig. 5 is an enlarged perspective view of a portion of the vertical sliding member of the load-supporting means and the overhanging arm extending therefrom, portions being broken away to illustrate the manner in which the arm is connected to the vertical sliding member.

One of the principal objects of the invention, as above stated, is to provide a light hoisting machine of rigid construction comprising a base, a standard which preferably is detachably connected thereto, and a load-supporting means of light construction desirably having an overhead arm overhanging the base and preferably so constructed that the load-supporting means can be readily assembled and removed from the standard for purpose of transportation.

In providing such a rigid and light construction the base, the standard, and the load-supporting means are formed of structural steel bars or plates which are welded together to provide in effect rigid, integral constructions.

In the preferred embodiment of the invention illustrated the base frame comprises a pair of parallel, structural steel side bars 1 and 2, preferably inverted angle bars which are connected together at their rear ends by a structural steel bar, preferably an angle bar 3 having its ends extending beneath the horizontal flanges of the side bar and welded both to the horizontal flanges and to the vertical flanges of the side bars. The front ends of the side bars are connected by an angle bar girder 4 which rests upon the horizontal flanges of the side bars and is welded thereto along the outer and inner edges which overlap the horizontal flanges of the side bars.

At the front end of the frame angle plates 5 and 6 are secured to the vertical flanges of the side bars 1 and 2. As shown, the vertical flanges 7 and 8 of these angle plates are welded to the side bars both along the front ends of the side bars and along the rear edge of the vertical flanges of the angle plates and along the lower edges thereof, thus providing a rigid construction in which the horizontal members of the angle plates extend outwardly from the side members. Ball bearing brackets 9 having casters 10 are secured to the under faces of the horizontal flanges 5 and 6 by bolts 11, thus providing

wheel supports for the front end of the base frame.

A shaft 12 is mounted in the vertical flanges of the side members 1 and 2 adjacent the rear end of the frame and rollers 13, preferably having ball bearings, are rotatably mounted on the shaft 12. The ends of the shaft 12 desirably extend slightly through the vertical flanges of the side bars and are welded thereto.

The construction thus produced provides a light and very rigid integral base frame.

The standard in the preferred construction illustrated comprises two vertical channel bars 14 and 15 which are reversely arranged with their respective flanges extending toward each other and in alignment and are spaced apart to provide a guideway for the load supporting means. The lower ends of these vertical channel bars are welded to an angle plate 16, preferably both along the top, the rear and bottom of the vertical flange of the angle plate, and the horizontal flange 17 of the angle plate desirably rests upon and is secured to the horizontal flanges of the side members by bolts 18. A plate 19, forming a brace, is welded at its upper end 20 to both front flanges of the channels and its lower end 21 is secured to the vertical flange of the angle plate 4 by a bolt 22. By reason of the fact that both the angle plate 16 at the base of the standard, and the brace 19, are detachably secured to the frame, the standard is easily removable for the purpose of transportation.

The vertical channels 14 and 15 of the standard are connected together near their upper ends by an angle plate 23, the vertical flange of which is welded to the rear flanges of both vertical channel bars. Plates 24 and 25 are welded to the extreme upper ends of the webs of the channel bars and extend forwardly and are drilled near their forwardly extending ends to receive a shaft 26 of a sheave 27 beneath which the horizontal flange of the angle plate 23 extends and serves to catch any drippings of oil from the shaft of the sheave. A winch-supporting bracket is secured to the front flanges of the channels of the standard, preferably about midway of the length of said standards. In the preferred construction illustrated this bracket

comprises a base 28 which is securely welded to the front flanges of the channel and has laterally extending flanges 29 and 30 in which the shaft 31 of a preferably spirally grooved drum 32 is rotatably mounted. The drum 32 is provided with a worm gear 33 which is engaged by a worm 34, the shaft 35 of which is mounted in bearings 36 and 37 which are welded to the inner face of the flange 29 of the bracket.

The load-supporting means comprises a vertical member preferably in the form of a hollow rectangular bar 38 which is slidably

mounted in the guideway provided by the separated flanges of the channel bars 14 and 15 forming the standard.

An arm 39, which is rigidly secured to the upper end of this vertical member or bar, extends rearwardly and overhangs the base frame, and desirably is provided at its outer free end with a plate 40 which is rigidly secured thereto, having at its ends preferably detachable means which may be connected to the article to be hoisted.

In the preferred construction the vertical sliding member 38 is formed of a structural steel channel 41 having a metal plate 42 engaging the edges of the flanges and secured thereto by lines of welding 43 of suitable length and spaced apart at suitable distances, (See Fig. 5). The horizontal arm 39 comprises a channel bar 44 of similar construction having a plate 45 engaging and welded to the edges of the flanges of the channel bar 44. The end 46 of the lower flange of the arm 39 rests upon the upper end of the vertical rectangular sliding member 38 and is secured thereto by lines of welding along the abutting surfaces.

In this construction the channel bars desirably are first welded together before the plate 42 is welded to the channel bar 38 or the plate 45 welded to the channel bar 44 and the plate 42 may extend to the upper face of the upper channel of the overhanging arm and welded along the abutting edges to increase the rigidity of construction, while the plate 45 of the overhanging arm may abut against the side of the plate 42 at its upper end and be welded thereto.

By virtue of this construction the load-supporting means comprises two hollow rectangular bars integrally connected forming a structure of relatively light weight and of maximum strength and rigidity. The plate 40 desirably is welded to the end of the overhanging arm 39 and is provided near its ends with notches 47 and 48 adapted to receive means for flexibly supporting the article to be carried from the plate.

Any suitable supporting means can be provided. As illustrated herein such supporting means comprises rods 49 having at their upper ends hooks 50 which engage the notches and at their lower ends other hooks 51 which desirably are disposed at right angles to the position of the hooks 50. These rods may be of any suitable length.

Suitable anti-friction means are provided for guiding the vertical member 38 of the load-supporting means in the standard. The preferred means comprises a shaft 52, which extends through apertures in the lower end of the vertical member 38, and is provided with rollers 53 which engage the outer faces of the rear flanges of the vertical channels forming the standard. A shaft 54, which is welded to the front face of the vertical load-supporting

member 38 at a distance from its end, is provided with rollers 55 which engage the inner faces of the same bars forming the vertical standard as are engaged by the rollers 53. A rod 56 is welded to the lower end of the member 38 and also engages the inner faces of said flanges.

A cable 57, which is connected at one end to a winch, extends over the sheave 27 and thence downwardly in the space between the channels forming the standard and at its lower end extends through a hole in the front wall of the vertical member 38 of the load-supporting means and is knotted or otherwise secured to the load supporting means.

In the operation of the device, the base frame of the truck, which is mounted upon casters and is very low, is backed beneath the refrigerator, platform or other device which supports the article to be lifted. The load-supporting means is then lowered by turning the handle of the winch until the depending rods or other connecting members can be readily attached to the article to be raised. These depending hooked rods desirably are so spaced that they can be readily introduced into the compartment of the refrigerator and attached to the power unit which is located therein. To hoist the device, the winch is wound up in the usual manner and the article raised to the desired height. The hoisting machine may then be readily pushed or pulled to the place at which it is desired to deposit the article which has been hoisted and the load-supporting means lowered by turning the handle of the winch in an unwinding direction. By reason of the fact that the winch is operated through a worm and gear, special locking devices are unnecessary.

By virtue of the construction above described, the overhanging arm can be raised to a considerable height above the top of the standard. This permits the use of a relatively short standard which will enable the hoisting machine to be passed through a doorway or beneath low-studded ceilings.

By virtue of the light construction of the hoisting machine, it can be readily transported in trucks and used in private houses and apartments to remove the power unit from refrigerators, and also may be used for such other purposes as may be required.

By reason of the detachability of the load-supporting means from the standard and the detachability of the standard from the frame, the hoisting machine can be readily crated for shipment in a minimum space. There are obviously many other features of practical advantage in construction and operation than those heretofore described.

It will be understood that the particular embodiment of the invention illustrated and described herein is of an illustrative char-

acter and not restrictive of the scope and meaning of the claims.

Having thus described the invention, what is claimed as new, and desired to be secured by Letters Patent, is:

- 5 1. A portable hoisting machine comprising a wheel-supported base frame, a standard extending upwardly from said frame in proximity to one end thereof formed of channel bars having their respective flanges facing each other and in alinement and so spaced apart that the edges of the rear flanges provide a guideway, load-supporting means comprising a vertical rectangular metallic bar 10 slidably fitting in said guideway having anti-friction guiding means engaging respectively the inner and outer faces of the rear flanges of said channel bars, a rigid arm extending rearwardly from the upper end of said sliding member and overhanging said frame, and means for raising and lowering said load-supporting means.
- 15 2. A portable hoisting machine comprising a wheel-supported base frame, a standard 25 rigidly connected to and extending upwardly from said frame in proximity to one end thereof formed of channel bars having their respective flanges facing each other and in alinement and so spaced apart that the edges 30 of the rear flanges provide a guideway, load-supporting means, comprising a vertical hollow metallic bar of rectangular cross section formed of a channel bar having a metal plate 35 welded to the edges of the flanges of said channel, slidably fitting in said guideway, and a similarly formed hollow arm welded to the upper end of said vertical member overhanging said frame, and means for raising and lowering said load-supporting means.
- 40 3. A portable hoisting machine comprising a wheel-supported base frame, a standard rigidly connected to and extending upwardly from said frame in proximity to one end thereof formed of channel bars having their 45 respective flanges facing each other and in alinement and so spaced apart that the edges of the rear flanges provide a guideway, load-supporting means, comprising a vertical hollow metallic bar of rectangular cross section 50 formed of a channel bar having a metal plate welded to the edges of the flanges of the channel, slidably fitting in said guideway, a shaft welded to the outer wall of said vertical member at the lower end thereof having 55 rollers engaging the outer faces of the rear flanges of the channel bars forming the standard, a shaft welded to the inner wall of said vertical member at a short distance from the 60 lower end thereof having rollers engaging the inner faces of said flanges, a rigid arm extending rearwardly from the upper end of said vertical member overhanging said frame, and means for raising and lowering said load- 65 supporting means.

4. A portable hoisting machine comprising a wheel-supported base frame, a standard rigidly connected to and extending upwardly from said frame in proximity to one end thereof formed of channel bars having their respective flanges facing each other and in alinement and so spaced apart that the edges of the rear flanges provide a guideway, load-supporting means comprising a vertical hollow metallic bar of rectangular cross section, 70 formed of a channel bar having a metal plate welded to the edges of the flanges of the channel slidably fitting in said guideway, a shaft welded to the outer wall of said vertical member at the lower end thereof having rollers engaging the outer faces of the rear flanges of the channel bars forming the standard, a shaft welded to the inner wall of said vertical member at a short distance from the 75 lower end thereof having rollers engaging the inner faces of said flanges, a rigid arm extending rearwardly from the upper end of said vertical member overhanging said frame, a winch mounted on said standard, a sheave mounted at the upper end thereof, and a cable extending from said winch over said sheave and connected to the lower end of said sliding member.

5. A portable hoisting machine comprising a wheel-supported base frame, a standard 95 formed of structural steel channel bars secured to and extending upwardly from said base frame and having their respective flanges facing each other and narrowly spaced apart to provide a guideway, load 100 supporting means comprising a hollow rectangular metallic bar slidably fitting in said guideway provided at its upper end with a rearwardly extending rigid arm overhanging said frame and having upper and lower 105 antifriction members engaging respectively the inner and outer faces of the rear flanges of said channel bars, a bracket welded to the front flanges of said channel bars, a winch drum having a shaft mounted in said bracket, 110 a worm gear connected to said winch drum, a crank shaft mounted in said bracket having a worm engaging said worm gear and operable upon rotation of said crank to rotate said drum, a sheave mounted upon the 115 upper end of said standard, and a cable connected at one end to said drum extending over said sheave and connected at its other end to the lower end of said bar.

In testimony whereof, we have signed our 120 names to this specification.

FREDERICK J. SHEPARD, JR.
NATHANIEL WARSHAW.
